JOURNAL BOX

Richard J. Brittain, Jr., Berkeley Heights, N. J., assignor to General Motors Corporation, Detroit, Mich., a corporation of Delaware

Application May 22, 1956, Serial No. 586,573

11 Claims. (Cl. 308—180)

This invention relates to antifriction journal boxes adaptable for supporting railway cars on rotatable axles and particularly to an improved bearing housing or saddle to be supported between the guides of the pedestals of a railway car truck.

Heretofore, it has been the practice to construct the various parts of railway journal boxes from castings which often were weak due to various imperfections such as blow holes, dirt inclusions, uneven cooling and other causes. Consequently, these castings have been large and heavy to assure the requisite strength to receive the shocks attendant with normal use. There has been much waste of material in these cast iron boxes and they have been expensive to manufacture due to expensive machining operations. Additionally, massive castings usually have to be subjected to seasoning operations. Some cast steel parts have been used in the fabricating of certain railroad journal boxes. However, these cast steel parts have also been massive and have required many expensive machining operations.

It is accordingly an object of the present invention to provide an improved journal box construction having many of its important parts formed from a single piece of sheet metal. Since such a housing assembly requires few cast metal parts, the present construction offers the advantages of not only being strong, but light in weight, less costly and more readily constructed. In addition to providing a journal box having these advantages, it is a further object of the present invention to provide an improved method of constructing a journal box by bending certain journal box parts to the required shape from sheet metal.

In accordance with the present invention, a journal box housing for railway bearings is principally composed of a sheet metal saddle member bent to form and requiring a minimum of machining operations. The housing assembly incorporating the journal box preferably encloses antifriction bearings rotatably receiving the car axle and transmitting the load of a railway car through the axle to the wheels, the rolling elements of these bearings being received in an outer race ring over which the sheet metal saddle conformingly fits. This sheet metal saddle is also provided with tangentially extending side flanges forming truck pedestal receiving channels, the upper portion of the saddle being arranged to carry the weight of the car thereabove.

To these ends and also to improve generally upon devices of this character, the invention consists in the various matters hereinafter described and claimed. In its broader aspects, the invention is not necessarily limited to the specific structures selected for illustrative purposes in the accompanying drawings wherein:

Figure 1 is a vertical sectional view of my improved journal box;

Figure 2 is a fragmentary plan view of my journal box with certain parts illustrated in central horizontal section;

Figure 3 is a fragmentary front end view partly broken away to show interior parts in vertical section;

2

Figure 4 is a plan view of the cut-out sheet metal saddle blank; and

Figure 5 is a perspective view of the saddle bent to final form.

5 An axle 10, upon which may be mounted suitable car wheels (not shown), is received within a journal box 12 for antifrictional rotation and for limited endwise movements by rows of cylindrical bearing rollers 14 that roll upon a hardened inner raceway sleeve 16 tightly pressed over a reduced end of the axle and which also roll against a hardened smooth cylindrical outer raceway 18 formed on a cylindrical outer race ring 20. The rollers of each row are circumferentially spaced by a rotatable cage 22. A freely floating spacer sleeve 24 is journalled on the outer raceway 18 and has its parallel flat end faces engageable with the inner ends of both sets of rollers to maintain these rollers in proper axial positions and in parallel relation to the axis of the axle 10. The inner end of the inner raceway sleeve 16 has an enlargement 26 fitting against an enlargement of the axle 10. This enlargement 26 is provided with a generally radially disposed annular shoulder 27 engageable with the ends of the rear set of rollers 14 to limit the extent of endwise movement of the axle in one direction as will be later described.

10 A front end cap 30 is demountably fastened to the forward end of the outer race ring 20 as by screws 31 passing through an annular end cap flange 32 which sealingly seats in position as by a suitable intervening gasket. An annular projection 34 extending axially from the flange 32 pilots within the end of the outer race ring 20. The inner end of this projection 34 terminates in a substantially radially disposed annular shoulder 36 which may be slightly spaced from the outer raceway 18 and 15 which has a flat end face for engagement by the flat ends of the front set of rollers 14 thus cooperating with the spacer sleeve 24 in preventing these rollers from skewing by guiding them in parallel relation to the axis of the axle 10. A forwardly extending portion of the end cap 30 has a counterbore 38 opening at its rearward end into the journal box in surrounding radially spaced relation to the reduced outer end of the axle 10. A cylindrical wall 39 of this counterbore terminates in a flat end wall 40 at the forward end of the cap 30.

20 A rear end cap 42 is demountably secured to the rearward end of the outer race ring 20 as by screws 44 passing through an end cap flange 46 and is provided with a through bore which receives in closely spaced relation the cylindrical periphery of the race ring enlargement 26. The end cap 42 may also be provided with a series of 25 axially spaced lubricant retaining grooves 48 opening radially inwardly towards the enlargement 26 to prevent lubricant leakage from the back of the journal box. If required, a suitable gasket may be located between the flange 46 and the end of the outer race ring 20 to prevent leakage of lubricant from the journal box. An annular projection 50 of the end cap 42 is piloted within the rearward end of the outer race ring 20, this projection terminating in a radially disposed annular shoulder 52 having a flat end face engageable with the flat end 30 faces of the rearward set of rollers 14 to cooperate with the spacer sleeve 24 in preventing skewing of the rollers by maintaining these rollers parallel to the axis of the axis of the axle 10. The spacing between the flat ends 35 of the roller engaging shoulders 36 and 52 is preferably such that both sets of rollers 14 may freely roll without assuming any appreciable endwise movement.

35 The axle 10 is permitted a limited endwise shifting movement which is cushioned at each end of its movement. This endwise shifting is free to occur since the cylindrical inner race ring may move endwise with the axle within the sets of cylindrical rollers 14. To cushion

the endwise movement of the axle 10, a thrust bearing 54, axially movable as a unit within the counterbore 38, includes an outer race ring 56 slidable in the counterbore and a rotatable inner race ring 58 with an intervening row of circumferentially arranged rollers 60 engaging raceways in both of these race rings. The inner race ring 58 has a flat end wall engageable with a flat outer end of the axle 10, this wall being provided with a lubricant groove 62 communicating with a central bore through this race ring 58. I preferably employ generally barrel-shaped rollers engaging a parti-spherical raceway in one of the race rings of the thrust bearing to assure flat abutting engagement of the end wall of the inner race ring against the end of its baffle. Lubricant within the journal box is distributed by the groove 62 to avoid wear of the abutting end faces of the axle and thrust bearing race ring 58. A resilient stack of Belleville washers or other suitable spring means 64 is axially slidably disposed within the counterbore and compressed between the flat end wall 40 of the end cap 30 and the flat end wall of the outer race ring. A plug 65 may be removed from the end wall 40 to provide an opening through which grease or other suitable lubricant may be fed into this journal box.

The resilient spring means 64 urges the bearing 56 as a unit towards the axle so that the inner race ring 58 engages and rotates with the axle while yieldably cushioning end thrusts of the axle towards the right as indicated by the arrow in Figure 1. The Belleville washers 64 preferably always remain sufficiently compressed to assure a driving engagement of the race ring 58 with the axle. With this arrangement any sudden shifts of the axle towards the thrust bearing will occur while the rollers 60 are in raceway rolling engagement thus avoiding any spalling damage to these raceways. The axial spacing between the shoulders 27 and 36 is preferably such that the endwise axle movement in the direction of the arrow is positively limited to prevent the Belleville washers 64 from becoming completely compressed thus avoiding the possible danger of spalling the raceways of the bearing 54 by the rollers 60. This endwise thrust of the axle is limited by engagement of the shoulder 27 with the rearward rollers, the thrust being transmitted through the sleeve 24 and forward rollers and limited by the shoulder 36. A similar journal box construction provided at the other end of the axle (not shown) permits a correspondingly limited cushioned shifting of the axle in the opposite direction.

A saddle member generally indicated at 70 and best illustrated in Figure 5, is bent to shape from a sheet metal blank 71. This blank is cut out in generally elongated rectangular form and has a pair of corresponding projections or flanges 73 laterally extending outwardly in opposite directions from its sides adjacent each end. These flanges, which preferably have tapered end portions 74, are each partially defined by an L-shaped slot 75 cut through the blank and extending laterally inwardly at an intermediate portion 77 of the blank and extending longitudinally of the blank to a position approximately opposite a mid portion of the adjacent flange 73. Corresponding slots 80 are cut laterally inwardly at the mid portion of the blank and the ends of the blank are provided with suitable bolt holes 82.

The blank 71 is bent from its initially flat form of Figure 4 to provide a semi-cylindrical central portion 84 extending throughout the length of the slots 75 and including the intermediate portion 77, this portion 84 being of a curvature to matingly seat against the upper half of the outer race ring 20 and having a width such that it fits between a rearward flange 86 of the outer race ring and the flange 32 on the front end cap 30 which preferably projects radially beyond the outer race ring. During this bending operation, the ends of the blank 71 are bent away from the intermediate portion 77 and away from the slots 75 to provide a pair of vertically parallel

end walls 88 and the flanges 73 are bent outwardly to project in substantially parallel rectangular relation to the end walls. These end walls 88 and outwardly extending flanges 73 provide a pair of spaced channels for slidably receiving the usual vertical pedestal portions of a railway car truck. I preferably secure as by welding or by other suitable method, wear plates 90 to the end walls 88 and wear plates 92 to the flanges 73 for slidably engagement with the truck pedestals. If desired, the inner face of the arcuate saddle portion 84 which seats against the outer race ring may be machined to assure desired seating conformity.

After the saddle member 70 is fitted over the outer race ring 20, a tie-bar or reinforcing plate 94 is secured as by bolts 96 between the lower ends of the side plates 88 and beneath the bearing. This reinforcing member adds rigidity to the journal box and preferably rests against the bottom of the outer race ring 20 to assure that the saddle 70 is properly held in position. The slotted portions 80 and 75 of the saddle provide laterally protruding lugs 98 that interfit within correspondingly located slots in the flanges 32 and 86 to prevent relative rotation between the outer race ring and the saddle 70. As an alternative construction, relative rotation between the outer race ring and the saddle may be prevented by one or more pins 100 mounted in correspondingly located bores in the saddle and the outer race ring.

An equalizer seat pad 102 of resilient wear resistant material covers a substantial area on the top curved portion 84 of the saddle member 70 and provides a seat for an equalizer plate 104 upon which the railway car truck rests, the weight of the railway car being transmitted through the equalizer plate and the seat pad to the journal box therebeneath. In view of the interfitting relation of the saddle on the outer race ring 20, the weight of the car above the journal box is distributed over a relatively large surface of the outer raceway 20 of the antifriction bearing and through a large number of the antifriction rollers 14, thence through the inner race ring 16 to the axle. Accordingly, a maximum number of the bearing rollers 14, rather than a few of the rollers just at the upper portion of the bearing, transmit the load to the journal as the rollers travel between the races. Hence, wear is minimized and the antifriction bearing lasts much longer. Due to my improved sheet metal saddle, which is bent to form, the resulting assembly is light in weight, relatively inexpensive, readily constructed, and of unusually rugged construction.

I claim:

1. In a journal box for a rotatable axle, a bearing including a cylindrical sleeve member in which the axle is rotatably received, end caps demountably fastened to the ends of said sleeve member, a unitary saddle member bent to shape from a single piece of sheet metal and receiving the cylindrical sleeve member, the saddle member having an intermediate curved portion fitted over and conforming to the cylindrical sleeve member between the end caps, side saddle walls at each side of the intermediate curved portion and extending above and below the axis of the sleeve member, and an intermediate portion of each side wall tangentially merging with said intermediate curved portion.
2. In a journal box for a rotatable axle, a bearing including a cylindrical sleeve member in which the axle is rotatably received, a unitary saddle member bent to generally U-shaped from a single piece of sheet metal and receiving said sleeve member, the saddle member having intermediate its length, a parti-cylindrical portion conforming with and fitted over the upper portion of said sleeve, side walls on said member tangentially extending in parallel relation from said parti-cylindrical portion at each side of the sleeve member, and a reinforcing member secured to and extending between said side walls below the sleeve member.
3. In a journal box for a rotatable axle, a bearing in-

cluding a cylindrical sleeve member in which the axle is free to rotate, a unitary saddle bent to generally U-shape from a single piece of sheet metal and receiving the sleeve member, the saddle having an intermediate part-cylindrical portion fitted over the cylindrical sleeve in conforming relation therewith, vertical parallel side walls on the saddle respectively located at each side of the sleeve and tangentially extending from the intermediate saddle portion, and a pair of spaced guide flanges bent out into laterally extending relation from each side wall.

4. In a journal box for a rotatable axle, a bearing including a cylindrical sleeve member for rotatably receiving the axle, a unitary saddle bent to shape from a single piece of sheet metal, the saddle having an intermediate curved portion fitted over and conforming to the upper portion of the cylindrical sleeve member, vertically disposed side saddle walls respectively located at each side of the sleeve member and tangentially extending from the intermediate curved portion, each side of said side walls laterally extending respectively beyond the adjacent end of said intermediate curved portion, a pair of spaced guide flanges laterally extending from each side wall, and wear plates secured to the side walls and to said flanges.

5. In a journal box having an antifriction bearing rotatably receiving an axle, a bearing outer race ring having a cylindrical periphery, a single-piece sheet metal saddle bent to shape and supported by the race ring, said saddle having an intermediate semi-cylindrical top portion seated on and conforming with the outer race ring, tangential side saddle walls merging with the semi-cylindrical portion and extending in substantially vertical parallel relation at each side of the outer race ring, each of the side portions having a pair of spaced laterally extending flanges providing guiding channels respectively at each side of the saddle, and a reinforcing member, demountably fastened at its ends to the lower ends of the side saddle portions.

6. In a journal box for a rotatable axle, an antifriction bearing rotatably receiving the axle and having an outer race ring, a unitary saddle member bent to shape from a single piece of sheet metal of uniform thickness and receiving said race ring, the saddle member having an intermediate arcuate portion conforming with and seated upon the upper portion of the race ring, parallel downwardly extending side saddle walls respectively tangentially merging with the intermediate arcuate portion at each side of said race ring, the sides of said walls extending beyond the arcuate ends of said intermediate portion, and means securing the race ring and saddle against relative rotation.

7. In a journal box for a rotatable axle, an antifriction bearing receiving the axle for rotation and for endwise shifting movements, said bearing including an outer race ring, an end cap secured in position at the outer end of the race ring, a thrust bearing slidably mounted in the end cap, resilient means in the end cap urging the thrust bearing into engagement with an end of the axle to cushion endwise shifting of the axle in one direction, and a saddle member bent to form from sheet metal and having an intermediate curved portion fitted in conforming relation over said outer race ring.

8. In a journal box for a rotatable axle, an antifriction bearing receiving the axle for rotation and for endwise shifting movements, said bearing including an outer

race ring, an end cap secured in position at an end of the race ring, a thrust bearing slidably mounted in the end cap and rotatably engageable with the end of the axle, a compressible spring member mounted in the end cap and yieldably urging the thrust bearing into axle engagement, means independent of the thrust bearing and limiting the endwise axle movement from completely compressing the spring member, and a sheet metal saddle bent to form and having an intermediate curved portion seated in conforming relation over the race ring.

9. In a journal box for a rotatable axle, an antifriction bearing receiving the axle for rotation and for endwise shifting movements, said bearing including an outer race ring, an end cap secured to an end of the race ring, 15 an antifriction thrust bearing slidably mounted in the end cap and having a rotatable thrust member engageable with the end of the axle, a compressible spring slidably mounted in the end cap and engaging the thrust bearing to maintain the thrust member against the axle for 20 yieldably cushioning endwise axle movement, shoulder means associated with the first mentioned bearing for limiting endwise axle movement from completely compressing said spring, and a sheet metal saddle secured to the outer race ring, said saddle having an intermediate 25 curved portion fitted over and conforming with an upper portion of the race ring.

10. In a journal box, an antifriction bearing for rotatably receiving an axle and including a horizontally disposed longitudinally extending sleeve forming an outer race ring, front and rear end caps demountably secured to said sleeve, a saddle bent to shape from a single piece of sheet metal and forming a housing for the sleeve, said saddle having an intermediate semi-cylindrical top portion seated upon and conforming with the upper portion 30 of said sleeve, downwardly extending side saddle portions tangentially extending in substantially parallel relation from said top portion, a pair of outwardly extending flanges bent out from the sides of each side saddle portion, interlocking mechanism preventing relative rotation of the sleeve and saddle, and means demountably securing the saddle to said sleeve.

11. In a journal box, an antifriction bearing for rotatably receiving an axle and including a horizontally disposed cylindrical sleeve forming an outer race ring, front and rear end caps demountably secured to said sleeve, an annular flange on one end of the sleeve, an annular flange on the end cap at the opposite end of said sleeve, a unitary sheet metal saddle housing the sleeve, said saddle having an intermediate semi-cylindrical top portion seated on and in conforming relation with the sleeve between said flanges, interlocking means between the sleeve and one of said flanges, downwardly extending substantially parallel side saddle walls tangentially extending from the semi-cylindrical top portion, and a reinforcing member extending between the side walls below said sleeve.
